ELECTRIC SIGNALING AND CONTROLLING APPARATUS

Lewis B. Winton, Wyncote, Pa., assignor to The Brown Instrument Company, Philadelphia, Pa., a corporation of Pennsylvania

Application September 21, 1929, Serial No. 394,278

5 Claims. (Cl. 200—5)

The present invention consists in an improved switch mechanism especially devised and adapted for use in a multiple switch relay forming a part of electric signaling and controlling apparatus in which one or more of a plurality of electrically controlled devices are selectively actuated accordingly as the value of a quantity being measured varies from a predetermined normal value. The devices so actuated may consist of, or actuate, indicating means for exhibiting the character of the variations, or may consist of, or actuate adjusting means tending to restore the quantity measured to its normal value on variations therefrom, or may consist of, or actuate, both indicating and adjusting means.

Apparatus of the above type is particularly useful in controlling furnace temperature conditions in installations in which the furnace temperature is measured by a thermocouple or thermometer and a control meter responsive thereto. In such apparatus a selective relay is usually associated with the control meter and actuated thereby to operate furnace control elements, which may be simple indicating devices, such as signal lamps, from the indications of which the furnace may be manually controlled. Automatic temperature adjusting devices may be used in lieu of or in addition to such indicating devices. The relay is operated in different ways when the furnace temperature is above, below and at the predetermined normal value. Apparatus of this general type is disclosed in the U. S. patent of Richard P. Brown, No. 1,443,165, granted January 23, 1923.

The general object of my present invention is to provide an improved switch mechanism primarily devised and especially adapted but not necessarily restricted to use in the selective relay of signaling and control apparatus of the above mentioned character. A relay adapted for such use and embodying the present invention is adapted to be selectively actuated in one way when the value of the quantity measured by the control meter is at a predetermined normal value, in a second way when it slightly exceeds the normal value, in a third way when it greatly exceeds the normal, in a fourth way when it falls slightly below normal, and in a fifth way when the fall is greater. When embodied in a furnace temperature control system in which the value of the temperature is indicated by means of three differently colored incandescent lamps, the latter are illuminated individually or in combination, accordingly as the relay is actuated.

55. The various features of novelty which charac-

terize my invention are pointed out with particularity in the claims annexed to and forming a part of this specification. For a better understanding of the invention, however, and the advantages possessed by it reference should be had to the accompanying drawing and descriptive matter in which I have illustrated and described a preferred embodiment of the invention.

Of the drawing:—

Fig. 1 is an elevation of a preferred form of my improved relay;

Fig. 2 is a section on the line 2—2 of Fig. 1; and

Fig. 3 is a wiring diagram illustrating the relay of Figs. 1 and 2 incorporated in electric signaling apparatus for temperature control.

In the drawing and particularly in Fig. 3, I have illustrated electric signaling apparatus for indicating variations in value of the temperature of a furnace and which comprises a control meter A having a galvanometer pointer A' arranged to move over a contact mechanism in accordance with the variations in value of the E. M. F. set up in a thermo-couple B, responding to the temperature of the furnace (not shown). The contact mechanism comprises a central contact N adjusted for the desired operating temperature, high and low temperature contacts H and L, respectively, at opposite sides of and slightly spaced from the central contact, and a contact table A² extending parallel to and co-extensive with the contacts L, N and H, as indicated. Periodically the pointer A' is depressed through a motor A³ energized from supply conductors 1 and 2 to establish an electric circuit between one of the contacts L, N or H then directly below it and the contact table A². The contact ends being only slightly spaced apart, the normal contact N can be simultaneously actuated with either of the contacts H or L when the pointer is in the proper position. The contacts N, L and H are connected to terminal posts N', L' and H' on the meter, while the contact table A² is shown connected to the supply conductor 1. The thermo-couple B is connected to the galvanometer element through conductors 3 and 4.

The terminal posts H', N' and L' are connected to corresponding terminal posts H², N² and L² of a selective relay mechanism D by conductors 5, 6 and 7, respectively. The relay D comprises three stationary electromagnets DH, DN and DL mounted on a base plate D' of insulating material. Each of the magnets has a coil D² surrounding a metallic core D³. A stationary control contact E is arranged at each side of each electromagnet coil and adapted to contact with a mov-

able contact E' positioned at the upper end of a flat elongated spring E². The springs E² for each pair of contacts have their lower ends connected to a horizontal bar E³ carried by an armature F, which has a vertical end portion F' with a horizontal pivotal connection F² with the base plate D'. The horizontal portion F³ of the armature extends outwardly below the electromagnet core D³ and adjacent its outer end is provided with upwardly projecting studs F⁴. By this arrangement the armature moves upwardly in a vertical plane into contact with the electromagnet when the latter is energized. By this movement the contacts E' and E are brought into contact with the springs E² flexed inwardly.

One terminal of the coils of each of the electromagnets DL, DN and DH is connected to the corresponding terminal posts L², N² and H², by conductors 5', 6' and 7', respectively. The second terminal of each coil is connected by branch conductors 9, 10 and 11 to a common conductor 8 leading to the supply conductor 2. The lower end of each contact spring E² associated with the electromagnets is also connected to the supply conductor 2 through short branch conductors 12, 13 and 14 connected to the conductors 9, 10 and 11, respectively. The corresponding control contacts E are connected to the terminal posts L³, N³ and H³, as shown in Fig. 3.

A lamp bank K, consisting of three differently colored incandescent lamps K', K² and K³, preferably colored respectively, green, white and red, is arranged in a position in which it can be quickly observed by the operator. One side of each lamp is connected to a corresponding terminal post H³, N³ or L², while the other side is connected to the supply conductor 1 through a common conductor 15. Snap switches J and J' are arranged in the conductors leading to the supply conductors whereby various parts of the controlling apparatus may be disconnected when desired. Safety fuses J² and J³ are also arranged in the energizing circuits of the relay and meter, respectively.

With the circuit connections described and the furnace temperature at a predetermined normal value, the galvanometer pointer A' will establish an electrical connection between the contact table A² and contact N in a well known manner. The electromagnet DN will consequently be energized causing the corresponding armature F to be drawn upwardly against the pole face of the core thereby closing the connection between the corresponding contacts E' and E and illuminating the lamp K². For other values of the furnace temperature above or below the normal temperature the circuits of the contacts L or H will be closed energizing the corresponding electromagnets DL or DH and illuminating the lamps K' or K³.

It is desirable that the indicating system produce a continuous indication of the furnace temperature so that the operator can be acquainted at all times with the operating conditions. To effect such an arrangement, the corresponding control contacts E' and E for each electromagnet must remain closed until one of the other electromagnets is energized and when that occurs the first pair of contacts must be opened, otherwise it is apparent that the signaling system would be inaccurate. The present relay mechanism therefore comprises means for mechanically effecting the above result. In the embodiment illustrated each armature is provided with a metallic plate M secured to its outer end and provided with an integral depending

stop M' bent outwardly at an angle to the plate M. A pair of bearing members O are positioned on the base plate D' below the armatures F³ and arranged to rotatably support a horizontal shaft O'. At spaced points on the shaft O' are keyed latch members P. Each of the latch members P comprises a vertical plate P' arranged in alignment with the corresponding armature stop M'. The inner edge of the plate P' is cut away in a predetermined manner, as shown in Fig. 2, to form a projecting shoulder P² adjacent its upper end. In the normal position of the latch the upper edge of the shoulder P² is inclined inwardly. One of the latch members, preferably the middle latch, is connected at its inner side to the base plate D' by a spiral spring Q, which constantly tends to move the shaft O' and latch members P towards the base plate.

With the parts constructed and arranged as described, on a normal furnace temperature indication the electromagnet DN will be energized causing the corresponding armature F³ to be drawn upwardly. During this movement of the armature the lower edge of the stop M' will contact with the vertical inner side of the latch shoulder P², causing the latch to be rotated outwardly against the tension of the spring Q. When the armature is in its uppermost position the stop M' contacts with the portion of the latch immediately above the shoulder P² and the circuit contacts E' and E are closed. The electromagnet energizing circuit remains closed only during the periodic intervals in which the pointer is depressed. In the interval between depressions the magnet DN is deenergized causing the armature F to be released. Due to the relative arrangement of the parts, the armature falls only a slight distance until the stop M' engages the upper edge of the shoulder P², as shown in Fig. 2. The flexure and location of the contact spring E² is sufficient to maintain the contacts E' and E closed during this movement of the armature and the lamp K² will remain illuminated.

Assuming that the furnace temperature now materially increases due to some change in the operating conditions, then the pointer A' will be deflected from its position above the contact N to a position above contact H and when the next depression of the pointer occurs, the circuit through the contact H and electromagnet DH will be closed and a movement of the corresponding armature F similar to that heretofore described, will occur. The magnet DN being now de-energized and its armature stop M' held in its intermediate position by the corresponding latch member only, the vertical movement of the armature of the magnet DH will cause the corresponding latch member to be moved outwardly, effecting a similar movement of the other latch members inasmuch as all are rigidly connected to the shaft O' and thereby removing the support for the armature of the electromagnet DN. The latter will then drop below the shoulder P², thus opening the circuit of the lamp K². The lamp K³ is now illuminated and will remain illuminated until the furnace temperature decreases.

The operation described is the same whether it is carried out in a system in which the lamps K', K² and K³ are individually illuminated only or where in addition to the individual illumination of the lamps, either of the lamps K' or K³ can be simultaneously illuminated with the lamp K².

K^2 to indicate slight deviations in either direction from the normal temperature value.

This result will be produced with apparatus of the type shown as a result of the fact that with 5 a certain slight deflection of the meter pointer A' to the low side of its neutral position, the contacts L and N are both connected to the contact A^2 , while on a certain slight deflection of the pointer to the high side of its neutral position 10 both contacts N and H are connected to the contact A^2 . In the one case the simultaneous energization of the contacts L and N will cause the simultaneous energization of the electromagnetic switch mechanisms DN and DL , and in the 15 other case, the simultaneous energization of the contacts N and H will cause the simultaneous energization of the mechanisms DN and DH . The following deenergization of the two electromagnets leaves their armatures both held in their 20 switch closing positions by the corresponding latch plates P as the armature of the electromagnet is shown as held in Fig. 2.

With the armatures of two of the electromagnets held in their switch closing position by the 25 corresponding switch latch members P' , it is apparent that the subsequent reenergization of either of said two electromagnets will not act through the corresponding part M' to rotate the shaft O sufficiently to release the armature of 30 the other electromagnet, even though the latter is then reenergized. To insure the release of the armature of one of two electromagnets previously simultaneously energized when only the other of those two electromagnets is reenergized, each 35 armature plate M is shown as provided with an integral depending hook member M^2 having its lower curved portion positioned at the rear of a laterally extending pin P^3 mounted on the corresponding latch plate P' . Each member M^2 is 40 arranged to coact with the corresponding pin P^3 so that when the armatures of any two electromagnets are held in their switch closing positions by the corresponding latch members the subsequent reenergization of one only of the said two 45 electromagnets will cause the hook M^2 pertaining to the electromagnet then reenergized to impact against the corresponding pin P^3 and thereby rotate the latch shaft O' against the action of the spring Q through a distance great enough to release the armature of the one of said two electromagnets which is not then reenergized. The 50 armature of the magnet then reenergized is held against the corresponding electromagnet core during the period of reenergization and resumes its latched position when the last mentioned electromagnet is deenergized, as the spring Q then returns the latch members to their latching positions.

With the foregoing relay construction and mode 55 of operation, it is apparent that with only three lamps in the bank, any one of the lamps may be individually illuminated and either of the lamps K' or K^3 simultaneously illuminated with the lamp K^2 so that the variations in value of the temperature are quickly and accurately indicated to the operator.

While in accordance with the provisions of the 60 statutes, I have illustrated and described the best form of my invention now known to me, it will be apparent to those skilled in the art that changes 65 may be made in the form of the apparatus disclosed without departing from the spirit of my invention as set forth in the appended claims and that in some cases certain features of my invention

may be used to advantage without a corresponding use of other features.

Having now described my invention what I claim as new and desire to secure by Letters Patent, is:

1. A relay mechanism comprising a plurality of electromagnets, an armature mounted adjacent each of said electromagnets and movable toward and away therefrom as the corresponding electromagnet is energized and deenergized, respectively, a contact mounted on each of said armatures and movable therewith, a stationary contact positioned adjacent each of said movable contacts and adapted to contact therewith when the corresponding electromagnet is energized, a common contact maintaining means actuated by the energization of any one of said electromagnets to maintain contact between the said contacts then brought into contact when said electromagnet is subsequently deenergized, and means actuated by the subsequent energization of another of said electromagnets rendering said first mentioned means inoperative. 80 85 90 95

2. A relay mechanism comprising a plurality of electromagnets, an armature positioned adjacent each of said electromagnets and movable toward and away therefrom as the corresponding electromagnet is energized and deenergized, respectively, a stationary contact adjacent each of said armatures, a contact resiliently supported by each of said armatures and adapted to contact with one of said stationary contacts when the corresponding electromagnet is energized, a common contact maintaining means including latching means associated with each electromagnet and actuated by the energization of any one of said electromagnets to maintain the corresponding contacts closed when said electromagnet is subsequently deenergized, and means for unlatching said latching means to open said contacts when another of said electromagnets is energized. 100 105 110 115

3. A relay mechanism comprising a plurality of electromagnets, an armature positioned adjacent each of said electromagnets and movable toward and away therefrom as the corresponding electromagnet is energized and de-energized, respectively, a stationary contact adjacent each of said armatures, a contact carried by each of said armature and adapted to contact with one of said stationary contacts when the corresponding electromagnet is energized, a pivoted latch member adjacent each armature and normally in contact therewith, said latch members being rigidly connected to one another, means on said armature for deflecting the corresponding latch member when the corresponding electromagnet is energized, and spring means for holding said latch member in a position to support said armature in an intermediate position when said electromagnet is subsequently de-energized. 120 125 130 135

4. A relay mechanism comprising a plurality of electromagnets, an armature positioned adjacent each of said electromagnets and movable toward and away therefrom as the corresponding electromagnet is energized and de-energized, respectively, a stationary contact adjacent each of said armatures, a contact carried by each of said armatures and adapted to contact with one of said stationary contacts when the corresponding electromagnet is energized, a pivoted latch member adjacent each armature and normally in contact therewith, said latch members being rigidly connected to one another, means on each armature for deflecting the corresponding latch member when the corresponding electromagnet is 140 145 150

energized, spring means for holding said latch member in a position to support said armature in an intermediate position when said electromagnet is subsequently de-energized, and separate means on said armature for deflecting said latch member when the corresponding electromagnet is energized while said armature is in the intermediate latched position.

5. A relay mechanism comprising a plurality of spaced electromagnets, an armature pivotally mounted adjacent each of said electromagnets and adapted to move toward and away therefrom as the corresponding electromagnet is energized and de-energized, respectively, a stationary contact adjacent each armature, a contact spring carried by each armature, a contact on said

spring adapted to contact with said stationary contact when the corresponding electromagnet is energized, a rotatably mounted shaft extending horizontally below said armatures, latch members secured to said shaft in alignment with said armatures, a shoulder formed on each of said latch members, a stop secured to each of said armatures, spring means normally maintaining corresponding latch members and stops in contact, said latch members and armatures being relatively positioned whereby when one of said electromagnets is energized, the corresponding armature stop engages said latch member shoulder to move said latch member outwardly against the action of said spring means.
